CLAIM

The ornamental design for a neck pillow as shown and described.

DESCRIPTION

FIG. 1 is a front, right and top perspective view of a neck pillow, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the neck pillow in a position of use; and,

FIG. 10 is another front, right and top perspective view of the neck pillow in another position of use.

The dashed broken lines depict portions of the neck pillow that form no part of the claimed design.

1 Claim, 10 Drawing Sheets
